UNITED STATES PATENT OFFICE.

JOHN F. LIVERS, OF KANSAS CITY, MISSOURI, ASSIGNOR TO THE BAILEY-REYNOLDS CHANDELIER COMPANY, A CORPORATION OF MISSOURI.

DESIGN FOR A LIGHTING-FIXTURE BANDING OR ARTICLE OF SIMILAR NATURE.

Application filed January 3, 1928. Serial No. 24,735. Term of patent 3½ years.

To all whom it may concern:

Be it known that I, JOHN F. LIVERS, a citizen of the United States of America, and a resident of Kansas City, county of Jackson, and State of Missouri, have invented a new, original, and ornamental Design for a Lighting-Fixture Banding or Article of Similar Nature, of which the following is a specification, reference being had to the accompanying drawing, forming a part hereof.

In the drawing:

Figure 1 is a front elevational view of the lighting fixture banding or article of similar nature; and

Figure 2 is a section on the line 2—2 of Figure 1.

I claim:

The ornamental design for a lighting fixture banding or article of similar nature substantially as shown.

JOHN F. LIVERS.
